CLAIM

The ornamental design for a hearing aid for the deaf, as shown and described.

DESCRIPTION

1. Hearing aid for the deaf

Figure 1.1 is a right perspective view of a hearing aid;

Figure 1.2 is a right side view of the hearing aid;

Figure 1.3 is a left side view of the hearing aid;

Figure 1.4 is a rear view of the hearing aid;

Figure 1.5 is a front view of the hearing aid;

Figure 1.6 is a top view of the hearing aid; and

Figure 1.7 is a bottom view of the hearing aid.

The portions of the hearing aid for the deaf shown in broken lines form no part of the claimed design.
